UNITED STATES PATENT OFFICE.

WILLIAM S. MARTIN, OF WAUKEGAN, ILLINOIS.

IMPROVEMENT IN CAR-BRAKES FOR RAILROADS.

Specification forming part of Letters Patent No. 41,013, dated December 22, 1863; antedated September 20, 1863.

To all whom it may concern:

Be it known that I, WILLIAM S. MARTIN, of Waukegan, in the county of Lake and State of Illinois, have invented a new and useful Improvement in Momentum Train-Brakes for Railroad-Cars; and I do hereby declare that the following is a full, clear, and exact description thereof, reference being had to the accompanying drawings and the letters and figures marked thereon, which form part of this specification.

In the said drawings, which are hereunto annexed, Figure 1 represents a longitudinal vertical section of a car with my invention attached; Fig. 2, a cross-sectional view of the same at the line *x* in Fig. 1; and Fig. 3 is a perspective view of the peculiarly-constructed lever, hereinafter described, by which my device is operated.

The nature of my invention consists in a novel arrangement, whereby the momentum of the cars or train operates as the power to wind up and apply the brakes to the train; and, also, in a novel device whereby the aforesaid arrangement will cease to operate upon the brakes when the maximum pressure desired is obtained.

To enable others to understand how to construct and use my invention, I will now proceed to describe the same with particularity.

A in the annexed drawings represents a wrought-iron shaft extending across the car between the two wheels of one truck, as shown, or near any pair of wheels of the car, and supported in suitable bearings in the hangers or pendent swinging supports, (marked F F'), which swinging supports are so arranged and attached to the frame-work of the car or truck as to enable the said shaft A, supported thereby, to move forward or backward, as may be desired.

B B' represent two friction-wheels, which revolve loosely upon the shaft A, and are so arranged thereon that when the said shaft is pressed forward, as hereinafter to be described, the circumference of the said friction-wheels is pressed against the circumference of the car-wheels, which thus cause the said friction-wheels B B' to revolve, if the cars are in motion.

To impart motion to the shaft A, I employ the following device, namely: the friction-

clutches C C', the springs S S', and the adjustable slides or bands D D'. The friction-clutches C C' are fixed upon the shaft A, so that the said clutches revolve with the shaft, and not upon it, as do the friction-wheels B B'. The adjustable sliding rings D D' are adjusted at any required position upon the shaft A, and fixed in such desired position by means of set-screws, or any other suitable device, and being thus fixed retain the springs S S' in place. The said spiral springs S S', being thus confined between the unyielding bands D D' and the friction-clutches C C', force said clutches against the said friction-wheels B B', so that the revolution of the said friction-wheels imparts a revolving or rotating motion to the shaft A so long as the resistance to the revolution of the shaft is less than the pressure of the springs S S' upon the clutches C C'. Through the said shaft A there is a hole, through which hole the chain *b* passes, which is attached at each end to the rods *c c'*, which extend to and are connected with the brake-levers *c c'*.

The object in having the chain *b* pass through the shaft A, as shown, instead of being fastened to it, is to cause the chain to so adjust itself in and upon said shaft that the pressure upon all the wheels of the car will be equal.

To operate my device herein described, I employ a lever of peculiar construction, (marked H in the drawings, and shown separately in Fig. 3.) This lever is supported upon a fulcrum at *h*, and in its configuration is adapted to the shaft A, as shown. To the upper end of the said lever the link-rods *d d'* are attached, which link-rods extend throughout the entire length of the train, being connected at each end of the cars by hooks or links, as shown in the drawings, or by any other suitable device, each car being provided with the aforesaid device, and the rods *d d'* being attached to the upper end of each lever. By the peculiar arrangement and construction of the said lever H, if the rod *d* is drawn, bringing the upper end of the said lever toward the left, the lower end thereof is thrown forward toward the right, thereby pressing the shaft A forward, so as to bring the friction-wheels C C' in contact with the car-wheels, as desired, and if the rod *d'* is drawn, bringing the upper end of said lever toward

the right, the lever is also pressed against the shaft A, throwing it forward, as before. At the points where the lever H is brought into contact with the shaft A, the anti-friction rollers a a' are inserted in such lever, so that the pressure of the lever upon the shaft A may not counteract or resist the revolution of the shaft, as caused by the friction-wheels B B', as aforesaid. The devices at each end of said shaft A being similar, the invention may be used with only one at one end of the shaft, or with both, as herein shown and delineated. The above brake is operated by means of a similar device upon the engine or tender, whereby the chains attached to the rods d d' are wound up on a shaft arranged in the same manner as the shaft A, and provided with the friction-wheels, clutches, springs, and adjustable slides hereinbefore described. By moving the slides D D' toward or from the clutches C C' the maximum of pressure capable of being made by the brakes is increased or decreased, respectively, and by the peculiar construction of the lever H the brakes are worked equally well, whether the car is moving backward or forward, by drawing upon the rods d or d'.

The operation of my invention is as follows: When the train is in motion, and it is desired to brake up the train, the engineer applies the power for that purpose, and the rod d or d' is drawn, thereby bringing the lever H against the shaft A, and forcing the friction-wheels B B' against the car-wheels, thereby causing the shaft A to revolve, winding up the chain b thereon, and bringing the brakes g g' g' against the car-wheels. When the maximum pressure of the said brakes, to which the springs S S' were adjusted, is reached, the friction-wheels revolve upon the shaft in spite of the pressure of the said springs, and thus the brakes may be kept up at such maximum pressure without danger of breaking the same, or the devices whereby they are operated; and when it is desired to release the brakes from their pressure upon the car-wheels, this is effected by releasing the strain upon the rods attached to the upper end of the lever H, when the wheels B B' are de-

tached from the car-wheels, and the back action or strain will at once revolve back the shaft A and unwind the chain b, restoring the brakes to their minimum of pressure. By having the friction-wheels B B' made fast upon the shaft A the friction-clutches, springs, and adjustable slides could be dispensed with; but some device for causing the shaft A to cease its revolution when the desired maximum of pressure is obtained would be necessary to obviate the danger of breaking the parts, or else the brakes would have to be released entirely from pressure upon the wheels, and could not be kept up at the maximum pressure, as they can by the employment of the aforesaid arrangement of the friction-clutches, springs, and slides, with friction-wheels B B' loose upon the shaft A. The friction-clutches C C' are provided with beveled or coniform recesses, into which a similar projection upon the friction-wheels B B' enters, the object of this arrangement being to obtain a greater amount of frictional bearing-surface than would be presented by plain surfaces.

What I claim as my invention, and desire to secure by Letters Patent, is—

1. The combination of the shaft A, the friction-wheels B B', the clutches C C', springs S S', and slides D D' with the chain b, arranged and operating substantially as and for the purposes herein delineated and described.
2. The peculiarly-constructed lever for moving the shaft A, (marked H,) whereby said shaft is moved forward in the desired direction, whether the lever H is moved forward or backward, arranged and operating substantially as shown and set forth.
3. Communicating motion to the friction-wheels B B' by the impact thereof upon the wheels of the cars, when said friction-wheels are used in combination with shaft A, the clutches C C', the springs S S', the slides D D', the lever H, and the chain b, operating as and for the purposes specified and shown.

W. S. MARTIN.
